RAIL TRACK TRAFFIC INDICATOR SYSTEM
Josef Fryba, 153 Madison Ave., Toronto, Ontario, Canada
Filed Apr. 21, 1959, Ser. No. 807,829
4 Claims. (Cl. 246—77)

The present invention concerns a system for relaying information as to railway traffic flow and may be utilized to operate a traffic control.

There has always been a necessity for some device or system by which it could be determined whether a given section of a railway line was free or occupied. There is a further need for a reliable traffic control system which will indicate not only when a train passes a certain spot but which will indicate in which direction the train is progressing and what portion of the train has passed over the spot.

To this end many devices, such as instant contactors or, as they are sometimes known, axle counters have been devised. Some of these devices are of the instantaneous or trip lever type whilst others are based on depression of a portion of the track, utilizing floating rails, etc. Many of these devices suffer from grave disadvantages as to reliability. Furthermore, these devices serve only to record or relay information as to the passing of a train, but they do not provide information as to the direction in which the train is travelling.

A particular advantageous device of this nature obviating many of the drawbacks of the prior art is disclosed in Canadian Patent No. 548,226 "Deflection Rail Contactor" dated November 5, 1957. Even this device by itself is not able to relay information concerning the direction of traffic flow and occupancy of various portions of the track.

This invention is designed to utilize a rail deflection contactor of the type described in Canadian Patent No. 548,226 in such a manner as to provide information vitally necessary to traffic control in railways.

Moreover, the present system which envisages the use of a rail contactor of the type mentioned provides a more reliable system in that the control section while giving a series of short impulses, is operated by means of an extended section of the rails (as opposed to the instantaneous contact devices and axle counters of the prior art) thereby eliminating false signals occasioned by oscillations created by shifting railway cars.

Accordingly, it is an object of the present invention to provide a railway track traffic indicator system.

It is a further object of the invention to provide a railway track traffic indicator system capable of providing information for recording not only traffic presence but direction of motion.

It is a further object of the invention to provide a railway track traffic indicator system capable of providing information for recording traffic quantity as well as direction of motion.

It is a further object of the invention to provide a railway track traffic indicator system capable of providing information for recording traffic presence, direction of motion and traffic clearance for given sections of track.

Other objects and advantages will become apparent from a consideration of the following description in conjunction with the drawings in which:

FIGURE 1 shows a portion of a railway track fitted with rail deflection contactors and showing the location of passing train wheels in diagrammatic form;

2

FIGURE 2 shows a wiring diagram for the connection of the rail deflection contactors of FIGURE 1 in accordance with the present invention and;

FIGURE 3 indicates schematically a system of the invention embodying control and intermediate sectors and relays within the control sectors for imparting information dependent upon train direction.

Referring now to FIGURE 1, there are shown in diagrammatic form, railway deflection contactors 10 and 11 disposed in rails 12 and 13 of the track. For a fuller description of the rail deflection contactors 10 and 11 reference is made to Canadian Patent No. 548,226, dated November 5, 1957.

For the purposes of the present invention it is sufficient to note that the rail deflection contactors of a particular control sector are designed to operate over an extended portion of the track for example four yards. It will be seen that rail deflection contactor 10 and rail deflection contactor 11 are positioned in semi-consecutive or partly overlapping relationship, so that when a train axle or wheel pair, for example wheel pair 14 moves from the position shown in FIGURE 1 and towards the position shown by wheel pair 15, it will cause the operation first of rail deflection contactor 10, then the operation of both contactors 10 and 11 and finally as it leaves the track section occupied by the contactors it will operate contactor 11 only. The contactors 10 and 11 may conveniently be overlapped to their mid portions, i.e. so that the whole extent between the beginning of contactor 10 and the end of contactor 11 would be approximately six yards. This distance can, of course, be varied depending upon the length of the rail deflection contactors. It is important that the total length of the control sector, i.e. that portion of the rail covered by contactors 10 and 11 should be less than the distance between axle 14 and axle 15, shown in FIGURE 1. This will cause intervals to occur between the operation of either of the contactors as a train passes. It will be noticed however, that axle groups may occur such as are represented by axle 15 and axle 16 where carriages are joined together or utilize group axles. The distance shown between axles 15 and 16 is less than six yards and it will become apparent that the occurrence of such a situation does not affect the operation of the invention as the axle group will operate in the same manner as a single wheel pair. In other words, although it is essential to the invention that intervals occur between the occupation of either of the contactors during the passage of a train, the system of the invention is not predicated upon an axle counter or wheel counter of the types known in the prior art.

It is only necessary that one interval occur for each passage of a car. Rail deflection contactor 10 is provided with a deflection switch 17 shown diagrammatically occupying position 18, when contactor 10 is undeflected, i.e. no train wheel is passing thereover, and occupying position 19, when rail contactor 10 is deflected, similarly rail contactor 11 is provided with deflection switch 20 occupying position 21 when the rail contactor is undeflected and position 22 when rail contactor 11 is in a deflected position.

Referring now to FIGURE 2 which shows a wiring diagram of a system of the invention, switches 17 and 20 are shown in positions 18 and 21 respectively, i.e. with rail deflection contactors 10 and 11 in the undeflected position. In this position it can be seen that no current can flow through switch 17 or 20 as contact in each line is broken

by one of the switches to be described hereafter in detail.

The following is a description of the operation of the device upon passage of a train from left to right, FIGURE 1. The reference numerals designated "prime" (') in FIGURES 2 and 3 relate to those portions utilized in a right to left direction of train travel to be considered hereinafter, corresponding to those portions used only in the left to right direction.

Stage 1.—Upon the approach of a train (from the left in FIGURE 1) rail deflection contactor 10 will be depressed causing switch 17 to move from position 18 to position 19 allowing current to flow through occupancy relay 24.

The activation of relay 24 causes switches 25, 26 and 27 to change position, and assume positions 28 and 29, 15 and break contact 30 respectively.

Switches 27 and 27' are normally in contact positions 30 and 30' and are activated to break-contact by the operation of relays 24 and 24' respectively.

With the switches in this position current can pass from a to b (FIGURE 2) but through no other line even though line k, l, is closed as line n, d, is broken by the breaking of contact 30.

The passing of current in line a-b can be utilized to activate a traffic presence indicator but such an operation is not essential to this invention although it provides a useful adjunct to it.

Stage 2.—Further movement of the train (to the right in FIGURE 1) now causes the activation of rail deflection contactor 11. It will be noted that due to the overlapping of contacts 10 and 11, contactor 10 is still operating at this stage, i.e. switch 17 is still in position 19.

Upon the operation of contactor 11, switch 29 is moved from position 21 to position 22, thus closing line c-1. Presence relay 24' is not operated because as previously described, contact 30 of switch 27 has been broken by the operation of presence relay 24.

Current is now free to pass through lines a, k, m, b, and through lines c, l, k, m, b. The purpose of this will become apparent from a consideration of the next stage.

Stage 3.—Further progress of the train axle 14 will bring it to a position where contactor 10 is released while contactor 11 is still deflected. The release of contactor 10 causes switch 17 to return to position 18. This would normally cause a break in the current flow through presence relay 24. But it will be noted that due to stage 2, current is still flowing along line c, l, k, m, b, and thus presence relay 24 is kept in operation, maintaining switch 25 in position 28 switch 26 in position 29 and switch 27 with contact 30 broken. The importance of this step should be emphasized in that it will be noted that with the passage of the train from left to right only presence relay 24 has been activated.

It will also be noted that at this stage switch 17 has resumed position 18. This allows current to flow along line a, e, f, because switch 26 is held in position 29 by relay 24. Thus current now activates delay relay 33. Relays 33 and 33' are designed to remain activated for a short period, e.g. $\frac{1}{10}$ of a second after current ceases to flow through them. Such types of relay are well known in telephone systems and are therefore not described further except to note that the delay feature is important as explained hereafter.

The operation of delay relay 33 causes switch 35 to assume position 36, but current cannot flow through relay 37 as switch 26 is held in position 29 by relay 24 and switch 38 is normally open as shown.

Stage 4.—As the train leaves the segment of rail covered by contactors 10 and 11, contactor 11 is deactivated causing switch 26 to resume position 21. Thus, relay 24 is immediately deactivated as current no longer flows along c, l, k, m, b. Immediately relay 24 is deactivated switch 25 moves from position 28 and switch 27 resumes

its normal closed position 30 (note no current will flow through relay 24' because switch 20 is in position 21).

Switch 26 is released from position 29 and resumes its normal position 39. This causes a break in line a, e, r, f, and current ceases to activate delay relay 33. However, as previously explained, relay 33 is a timed delay relay and maintains its effect after deactivation for a given period say $\frac{1}{10}$ second. During this period switch 35 remains in position 36 and switch 25 is in position 39 so current can flow along p, q, r, f, activating relay 37. The period of operation of relay 37 is thereby fixed to the delay of delay relay 33 and thus relay 37 is a fixed period relay or constant impulse relay. There is one possibility that should rail deflection contactor 10 be operated by a further train wheel arriving on that portion of the track before the delay period of relay 33 expired, the switch 26 would be returned to position 29 thus breaking the circuit p, q, r, f and altering the time of operation of relay 37. In order to obviate this, relay 37 is designed upon activation to operate switch 38 (normally open) to close switch 38 to position 40. Thus, current is free to flow along p, q, s and the beginning of a new Stage 1 of the cycle and the return of switch 26 to position 29 will not affect the current flow through relay 37. As soon as delay relay 33 dies, switch 35 will open and current will cease to flow. Relay 37 is thus ensured of a constant period of operation.

It has now been shown that the passing of a train axle 14 will cause relay 37 to be operated for a fixed period which may be utilized to deliver a fixed impulse (to be explained hereinafter).

Cases may occur where the distance between axles is less than the total extent of the control sector of the rails. Such a situation is represented by axles 15 and 16 (FIGURE 1). Under these circumstances it will be seen that no harm occurs, as relay 37 is only operated upon the clearance of the control sector. The departure of axle 16 from the end of the control sector of the track will not operate relay 37 as axle 15 will still be causing Stages 1, 2 or 3 described above to be in operation preventing cut out of relay 24. Thus, under these circumstances, only one impulse will be delivered to or by relay 37. It is here again emphasized that this invention does not provide a wheel or axle counter. However, a specific determinable number of impulses will occur with the passage of any particular train.

Reverse operation

The foregoing description of operation of the device by a train proceeding in a left to right direction may be repeated for operation in the right to left direction, though utilizing components designated "prime" ('). The designation "prime" (') indicates portions of the device only used in the right to left direction but corresponding to those used in the left to right direction.

It will be apparent that when proceeding from right to left a train will first depress deflection contactor 11, then contactor 10 and 11, thence releasing contactor 11 and finally releasing contactor 10 in the reverse order as described for left to right travel. In this manner relays 24', 33' and 37' will each be operated by means of switches and switch positions identical to those used in operation of relays 24, 33 and 37. Switches 17 and 29 are utilized when the train approaches from either direction since they are directly related to the deflection of contactors 10 and 11 respectively.

Referring now to FIGURE 3: which shows diagrammatically a long section of railway line having section A and section B with control section C₁ interposed therebetween, and control section C₂ between section B and next adjacent section D. Each of these control sectors C₁ and C₂ comprises the rail deflection contactors of FIGURE 1 and the circuitry of FIGURE 2 with relays 37 and 37' shown diagrammatically for each of control sectors C₁ and C₂ respectively.

Thus as previously described, a train passing from A to B will cause a given number of impulses to be delivered by relay 37 in sector C₁. As previously described these impulses (or even the earlier operation of relay 24) may be used to activate an occupancy indicator, but it is contemplated that this invention could be used as follows:

The relays 37, (left to right direction) and 37' (right to left direction) operate a control device (not shown), in the manner following, for example as a train passes out of section A into section B the passage of the train over the deflection contactors 10 and 11 (FIGURE 1) in control section C₁ causes the operation of the circuitry shown in FIGURE 2 as previously described and delivers X impulses from relay 37 (C₁). This information is caused to operate an "occupied" signal for section B. Upon leaving section B and entering section D the train will cause the same number of impulses X to be delivered from relay 37' of control section C₂. This is arranged through suitable means known to the art, to release the occupied signal for section B. It will be noted, however, that as relays 37 etc. give an impulse of definite duration it is possible to arrange a system whereby the number of impulses are recorded, as the "occupied" signal can only be released by a similar number of impulses from relay 37', (C₂) showing that the whole train has passed on to section D, or alternatively be released by a similar number of impulses from relay 37' (C₁) showing that the whole train has reversed and passed back onto section A. The release impulses from relay 37' (C₁) would also serve to operate the "occupied" signal for section A.

For example, should a train delivering X impulses to the control system C₁ pass from A to B and then detach part of the train leaving some cars in section B it will deliver a lesser number of impulses say (x-y) to control system C₂ (relay 37) as it passes to section D. The x-y impulse delivered to relay 37 (C₂) will operate the occupied signal for section D but will be insufficient to free the occupied signal for section B, showing that cars have been left on the tracks.

It will thus be seen that the system of the invention can be utilized in a variety of ways to provide superior information as to the direction and extent of traffic flow and occupancy of the tracks and concomitantly superior control means for train traffic.

The relays and delay relays referred to in this invention can be of known types, for example, similar to those used in current telephone systems and thus the advantage of comparative cheapness can be added to those advantages already enumerated.

The advance in the art provided by the instant invention will permit the operation of various control systems and it is contemplated that the invention may be utilized not only on straight tracks but on sidings, switch lines, crossings, etc.

It will be appreciated and is contemplated that variations and modifications may be made within the spirit and scope of the invention as defined in the following claims.

What I claim is:

1. A railway track traffic indicator system comprising: presence relay means intermittently operated by the passing of a train; delay relay means operable during part of the period of operation of said presence relay means; relay means operable upon deactivation of said presence means and of the said delay relay means providing a predetermined duration signal independent of the period of operation of said presence relay means and said delay relay means; second presence relay means intermittently operated by the passing of a train; delay relay means associated with said second presence relay means and operable during part of the period of operation of said presence relay means; second relay means operable upon deactivation of said second presence relay means and said asso-

ciated delay relay means to provide a predetermined duration signal independent of the period of operation of said second presence relay means and said associated delay relay means; first and second actuator means actuating said presence relay means; said actuator means being disposed in opposite rails in the track in semi overlapping staggered relationship whereby said actuators will be operated in sequence by the passage of a train wheel pair; and holding switch means associated with each said presence relay means whereby the first actuated of said presence relay means is held in operation throughout the actuation of both said actuators.

2. A railway track traffic indicator system comprising: at least one control sector in the track; a first rail deflection contactor and a second rail deflection contactor disposed in partially overlapping staggered relationship in opposite rails of the track; separate relay means normally actuatable upon operation of said first or second rail deflection contactors respectively; holding switch means operated by the first activated of said presence relay means to maintain the operation of said first activated presence relay means during occupancy of the control sector by a train wheel pair and to prevent operation of the presence relay means normally operated by the other rail deflection contactor; delay relay means having a predetermined delay period after deactivation, said delay relay means being operable during part of the period of operation of said activated relay means; switch means operated by said delay relay means and held thereby after deactivation thereof during the period of delay of said delay relay means; and means actuatable upon deactivation of said presence relay means and said delay relay means during the period of delay of said delay relay means thereby producing a predetermined duration signal contact.

3. A railway track traffic indicator system comprising: at least one control sector in the track; a first actuator means disposed over a portion of one rail of said control sector; a second actuator means disposed over a portion of the other rail of said control sector, said actuators being in staggered overlapping relationship; a first presence relay circuit operated by said first actuator means; a second presence relay circuit operated by said second actuator means, one of said first or second presence relay circuits being closed upon initial activation of one of said first or second actuator means respectively; switch means operated by the first activated presence relay circuit to break the other presence relay circuit; switch means operated by the first activated presence relay circuit to hold said circuit closed during the operation of both actuator means; a first delay relay circuit in parallel with said first presence relay circuit; a second delay relay circuit in parallel with said second presence relay circuit; switch means operated by said activated presence relay means to partially complete the circuit in the associated parallel delay relay circuit; switch means associated with said actuator means to complete the said partially completed parallel delay relay circuit upon the release of said first activated actuator means; a separate indicator relay circuit in parallel with each said first and second presence relay circuits; switch means in said indicator relay circuits and responsive respectively to activation of said first or second delay relay means to partially close one of said circuits; further normally closed switch means in said indicator relay circuits said switch means in said partially closed indicator relay circuit being held open by the operation of said activated presence relay means, whereby upon deactivation of said activated presence relay means said last mentioned switch closes, completing the one indicator relay circuit, said circuit remaining closed during the predetermined delay period afforded by the activated delay relay means thus permitting a predetermined duration signal impulse to pass through the circuit, and a holding switch means in said indicator relay circuit whereby reactivation

60 with each said first and second presence relay circuits; switch means in said indicator relay circuits and responsive respectively to activation of said first or second delay relay means to partially close one of said circuits; further normally closed switch means in said indicator relay circuits said switch means in said partially closed indicator relay circuit being held open by the operation of said activated presence relay means, whereby upon deactivation of said activated presence relay means said last mentioned switch closes, completing the one indicator relay circuit, said circuit remaining closed during the predetermined delay period afforded by the activated delay relay means thus permitting a predetermined duration signal impulse to pass through the circuit, and a holding switch means in said indicator relay circuit whereby reactivation

of the presence relay means does not interrupt said circuit before the expiration of said predetermined period.

4. A railway track traffic indicator system as claimed in claim 3 in which the actuator means overlap each other by approximately half their length.
